COMPUTER CONSOLE

Eliot Noyes, New Canaan, and Ernest M. Bevilacqua,
Springdale, Conn., assignors to International Business
Machines Corporation, New York, N.Y., a corporation of New York

Filed Dec. 23, 1960, Ser. No. 63,317

Term of patent 14 years

(Cl. D26—5)

FIG. 2

FIG. 1 is a perspective view of the front and right hand side of a computer console showing our new design; and

FIG. 2 is a perspective view of the rear and left hand side thereof.

We claim:

The ornamental design for a computer console, substantially as shown.
